CLAIM

The ornamental design for a drawing-out tool for sheet metal as shown and described.

DESCRIPTION

FIG. 1 is a front view of a drawing-out tool for sheet metal showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof;

FIG. 8 is a detail front view of a surface contact section in a leg composing the drawing-out tool for sheet metal shown in FIG. 1;

FIG. 9 is a detail rear view thereof;

FIG. 10 is a detail top view thereof;

FIG. 11 is a detail bottom view thereof;

FIG. 12 is a detail left side view thereof;

FIG. 13 is a detail right side view thereof; and,

FIG. 14 is a detail perspective view thereof.

The broken lines are for illustrative purposes only and form no part of the claimed design.

1 Claim, 8 Drawing Sheets
